UNITED STATES PATENT OFFICE.

LEO GUDEMAN, OF NEW YORK, N. Y.

DESIGN FOR AN ILLUMINATED TABLE DECORATION.

43,532.

Specification for Design.

Patented Feb. 11, 1913.

Application filed October 2, 1912. Serial No. 723,642. Term of patent 3½ years.

To all whom it may concern:

Be it known that I, LEO GUDEMAN, a citizen of the United States of America, residing at New York, in the county of New York and State of New York, have invented a new, original, and ornamental Design for an Illuminated Table Decoration, of which the following is a specification, reference being had to the accompanying drawing, forming part hereof.

The drawing is a perspective view of an

illuminated table decoration showing my new design, said table decoration being circular in cross section.

I claim:

The ornamental design for an illuminated table decoration as shown.

LEO GUDEMAN.
